UNITED STATES PATENT OFFICE.

JAMES F. McELROY, OF ALBANY, NEW YORK, ASSIGNOR TO THE CONSOLIDATED CAR-HEATING COMPANY, OF SAME PLACE.

DESIGN FOR AN ELECTRIC-HEATER CASE.

SPECIFICATION forming part of Design No. 28,327, dated March 1, 1898.

Application filed November 2, 1895. Serial No. 567,765. Term of patent 14 years.

To all whom it may concern:

Be it known that I, JAMES F. McELROY, a citizen of the United States, residing in the city and county of Albany, State of New York, have invented and produced a new and original Design for Electric-Heater Cases, of which the following is a specification, reference being had to the accompanying drawings, forming a part thereof.

10 Figure 1 is a front elevation. Fig. 2 is a cross-section.

The front plate is of oblong shape and of a flat surface.

I arrange a plain border A, extending entirely around the plate. In the interior of the border are two long narrow strips B C, each containing a series of openings, said strips separated from each other by a centrally-closed or plain surface D. To the rear 20 of the plate A, I arrange a concavo-convex

casing E, inclosing a partition-plate F, forming substantially to the casing E, but separated therefrom through a part of its length, as shown in Fig. 2.

The leading feature of my design consists in an electric-heater case having its front plate substantially of a flat surface, a plain border, two narrow strips each containing a series of openings arranged interiorly of the border on opposite sides of a panel or plain surface, substantially as described.

What I claim as my invention, and desire to secure by Letters Patent, is—

The design for an electric-heater case as herein shown and described.

JAMES F. McELROY.
